(57) **CLAIM**

The ornamental design for a headwear accessory of VR glasses, as shown and described.

DESCRIPTION

FIG. 1 is a perspective view of a headwear accessory of VR glasses design showing my new design.

FIG. 2 is a front view of a headwear accessory of VR glasses.

FIG. 3 is a rear view of a headwear accessory of VR glasses.

FIG. 4 is a left side view of a headwear accessory of VR glasses.

FIG. 5 is a right side view of a headwear accessory of VR glasses.

FIG. 6 is a top view of a headwear accessory of VR glasses.

FIG. 7 is a bottom view of a headwear accessory of VR glasses.

FIG. 8 is a front, right side perspective view of a headwear accessory of VR glasses.

FIG. 9 is an enlarged view of the headwear accessory of VR glasses taken from the circle part in FIG. 1.

FIG. 10 is an enlarged view of the headwear accessory of VR glasses taken from the circle part in FIG. 8.

FIG. 11 is an enlarged view of the headwear accessory of VR glasses taken from the circle part in FIG. 2.

FIG. 12 is an enlarged view of the headwear accessory of VR glasses taken from the circle part in FIG. 3.

FIG. 13 is an enlarged view of the headwear accessory of VR glasses taken from the circle part in FIG. 4.

FIG. 14 is an enlarged view of the headwear accessory of VR glasses taken from the circle part in FIG. 6; and,
FIG. 15 is an enlarged view of the headwear accessory of VR glasses taken from the circle part in FIG. 7.

The broken lines in the drawings depict portions of the headwear accessory of VR glasses that form no part of the claimed design.

Any shading and cross-hatching are not features of the design but are utilized to illustrate the surface contours of the headwear accessory of VR glasses design in the drawings.

1 Claim, 15 Drawing Sheets
